F. A. GERCICH

SPLASHER BACK FOR STOVES

Filed Aug. 1, 1925

Patented June 21, 1927.

1,633,089

UNITED STATES PATENT OFFICE.

FREDERICK A. GERCICH, OF OAKLAND, CALIFORNIA.

SPLASHER BACK FOR STOVES.

Application filed August 1, 1925. Serial No. 47,409.

My invention relates to a splasher back structure for stoves, and is particularly adapted for use on stoves having an oven positioned laterally of and extending above the level of the cooking top of the stove.

An object of the invention is to provide, in a stove of the character described, a one-piece rear splash plate which is so formed that no visible corner is defined at the intersection of the planes of the plate and another surface such as the side of the oven, and which may be effectively and directly secured to such oven or the like without the use of separate attaching strips or plates.

Another object of the invention is to provide, in a stove of the class described, a splasher back having an upper section arranged to extend completely across the stove and to be held in position without the use of bolts or similar fastening means.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figure 1 is a perspective view of a stove equipped with the splasher back of my invention.

Figure 2 is an enlarged fragmentary sectional view taken on the line 2-2 in Figure 1.

Figure 3 is an enlarged fragmentary sectional view taken on the line 3-3 in Figure 1.

Figure 4 is an enlarged fragmentary sectional view taken on the line 4-4 in Figure 3.

Figure 5 is a fragmentary view similar to that of Figure 2, but showing a splash back of different shape at its end.

As here shown, the splasher back 5 of my invention is applied to a stove 6 having a cooking top 7 and an oven 8, the latter being disposed to a side of and extending above the level of the former so that a side wall 9 thereof extends upwardly from the cooking top at one end. The splasher back is prefer-

ably formed with plate sections 11 and 12, the former being vertically disposed in the space directly back of the cooking top and arranged to extend substantially to the level of the oven top 13, while the latter is arranged to extend as a continuation of the former across the full length of the stove above the section 11 and the oven top. Support for the splasher back sections 11 and 12, it will be noted, is hereby shown provided by means of their suitable attachment to the oven at one end and by means of a common supporting bracket 14 positioned at the other end and fixed to the cooking top.

As is well known, the removal of greasy products, and particularly such as those produced by the cooking process, is at best difficult, and particularly so from any crevices existing in the surface of lodgement. Obviously the right angle corner defined at the intersection of the splash plate 11 and the oven wall 9, would present the before mentioned difficulty of cleaning, and the elimination of such difficulty is, as hereinbefore stated, an object of my invention.

As here shown, the plate 11 is formed with a vertically disposed corrugation or offset 16 extending forwardly therefrom and adjacent a side edge portion 17 arranged to lie against and be secured to the back wall 18 of the oven. The offset 16, it will be noted, as shown in Figure 2, comprises a substantially quarter arc portion 19 curving forwardly from the front surface of the plate 11 to a transversely extending portion 21, defining a face which is arranged to abut the oven wall 9 when the plate 11 is properly positioned thereagainst. In this manner, the offset serves to provide the equivalent of a mold filler for the corner defined by the plate 11 and wall 9, but since in the present structure the offset is integral with the plate 11, the problem of fixing a separate bead of appropriate shape in such corner is entirely avoided.

While the offset is here shown as having the external form of a mold, it will be obvious that other forms such as the quarter round offset 22 shown in Figure 5 may be utilized to the same or equal advantage. It will further be obvious that a similar offset may, if desired, be provided in the plate at its other end adjacent and cooperating with the bracket 14 for attachment thereto. The bracket 14 is preferably formed with lower and upper

sections 23 and 24 respectively, the section 23 extending from the stove cooking top to the level of the oven and arranged to have the lower splash plate 11 fixed thereto, 5 while the upper section 24 is arranged to cooperate with a bracket 26, preferably of like form, removably fixed on the top of the oven, to hold, in a manner to be hereinafter described, the upper plate 12. As here 10 shown, there is provided a shelf 27 provided with downwardly extending end flanges 28, and an offset longitudinally extending portion 29 is conveniently included in the splasher back structure under which the rear 15 edge of the bracket engages, it being noted that the shelf is preferably positioned on a level with the oven top and between it and the bracket, and is arranged to be secured by means of the appropriate flanges both to 20 the oven side 9 and splash plate 11 at their respective top edges in any desired manner. The end flange 28 which registers with the bracket 14, it will be particularly noted, is arranged to be secured to the bracket by 25 means of the same bolts 32 which fix the bracket sections 23 and 24 together.

Referring more particularly to the upper bracket section 24 and the bracket 26 mounted on the oven, it will now be noted that the 30 opposing faces thereof are provided with forward and rear bosses 33 and 34 extending therefrom and so arranged that when the ends 36 of the upper plate 12 are positioned between and abutting the brackets, the plate 35 ends will engage with and between the bosses in such manner as to prevent the movement of the plate in any direction. In this manner, the plate 12 is arranged to be gripped in position without the necessity of perforating the same or providing special holding means. The forward boss 33, it will be 40 noted, preferably extends substantially the full height of the plate, so that a particularly neat joint is provided which conceals the plate end 36 when viewed obliquely from the front. The structure herein described, 45 it will now be noted, allows the assembly of the upper portion of the splasher back independently of that of the lower portion, 50 which feature is particularly valuable in packing a stove for shipment, since the brackets 24 and 26 and the plate 12 may be omitted from a primary assembly of the stove parts and yet be readily positioned 55 after the destination is reached and the stove is unpacked.

I claim:

1. In a stove having a cooking top and an oven positioned laterally of and extending 60 above the level of the cooking top; a splash plate arranged to lie at the rear of the cooking top with the major portion thereof substantially coplanar with the oven back and having an intermediate portion arranged to 65 contact with a side of said oven forwardly

of said plane and having an end portion adjacent said intermediate portion fixed to said oven.

2. In a stove having a cooking top and an oven positioned laterally of and extending 70 above the level of the cooking top, a splash plate arranged to lie at the rear of the cooking top and having an edge arranged to be fixed to the rear wall of the oven, said plate having an intermediate portion thereof arranged to lie along the adjacent side of the oven.

3. In a stove having a cooking top and an oven positioned laterally of and extending 80 above the level of the cooking top; a splash plate arranged to lie at the rear of the cooking top substantially in the plane of the back wall of the oven and having an edge portion with its face arranged to engage the back wall of said oven, and a vertically disposed integral corrugation extending forwardly from said plate of substantially quarter-round section arranged to lie in the corner defined at the juncture of the said plate and adjacent side of said oven.

4. In a stove having a cooking top and an oven positioned laterally of and extending 90 above the level of the cooking top, a splash plate arranged to be fixed at the rear of the cooking top substantially in the plane of the back wall of the oven and extending to the level of said oven, said plate being formed with a vertically disposed corrugation extending forwardly therefrom adjacent an edge thereof and arranged to lie in the corner defined by the planes of said plate and the intersecting side of said oven, a bracket arranged to be fixed at the other edge of said plate, a horizontal shelf plate connected to and between said bracket and said side 100 of the oven substantially in the plane of the top of said oven, a back plate positionable in a vertical plane above and at the rear of said shelf and oven top, and cooperating brackets respectively attachable to said first bracket and the outer side of said oven arranged to engage and hold said back plate positioned between them.

5. In a stove having a cooking top and an oven positioned laterally of and extending 110 above the level of the cooking top, a splash plate arranged to be fixed at the rear of the cooking top substantially in the plane of the back wall of the oven and extending to the top and to the adjacent edge of said oven, a bracket fixed at the free side edge of said plate, a horizontal shelf plate connected to and between said bracket and the adjacent side of the oven, a back plate positionable in a vertical plane above and at the rear of said shelf and oven top, cooperating brackets respectively attachable to said first bracket and the outer side of said oven, and means formed integral with said cooperating brackets arranged to engage opposite sides of said 120 130

back plate and hold the same vertically positioned between said brackets.

6. In a stove having a cooking top and an oven positioned laterally of and extending above the level of the cooking top adjacent one end thereof, a bracket positioned at the other end of said top and extending above the level thereof, a splash plate at the rear of said top and having one end fixed to said oven and the other end to said bracket, said plate having a vertically disposed integral corrugation adjacent each of said ends thereof and lying in the corners respectively at the juncture of said plate and oven and at the juncture of said plate and bracket.
7. In a stove having a cooking top and a

stove member extending above the level of said top and positioned adjacent the juncture of the adjoining sides thereof, a splash plate extending upwardly from one of said sides of the top, means to secure an end of said plate to said member, and a vertically disposed integral corrugation formed in said plate adjacent said end arranged to lie in the corner defined at the juncture of said plate and member to conceal said securing means.

In testimony whereof, I have hereunto set my hand at Oakland, California, this 10th day of July, 1925.

FREDERICK A. GERCICH.
